EXPANSIBLE CABINET

Clarence A. Troutman, High Point, N. C.

Application July 13, 1951, Serial No. 236,527

2 Claims. (Cl. 248—129)

1

This invention relates to expandable cabinets, and more particularly to an expandable cabinet base for a television or radio set.

It is among the objects of the invention to provide an improved expandable cabinet which is adjustable or variable in width to accommodate television or radio sets of different widths and can be locked in selected adjusted positions; which includes slidable elements extending between the side panels of the cabinet for maintaining the side panels substantially parallel to each other while the cabinet is in expanded or contracted condition; which is strong and rigid in construction to safely support a heavy television or radio set; which has a shield or screen covering the front panel of the cabinet to conceal the relatively movable portions of the front panel, the screen being designed to carry out the decorative motif of a television set to be supported on the cabinet; and which is economical to manufacture, easy to adjust, and neat and attractive in appearance.

Other objects and advantages will become apparent from a consideration of the following description and the appended claims in conjunction with the accompanying drawing wherein:

Figure 1 is a perspective view of an expandable cabinet illustrative of the invention;

Figure 2 is a cross sectional view on the line 2—2 of Figure 1; and

Figure 3 is a cross sectional view on the line 3—3 of Figure 1.

With continued reference to the drawing, the cabinet comprises a pair of vertical side frames 10 and 11, of open rectangular shape, disposed in spaced apart and substantially parallel relationship to each other, and a pair of side panels 12 and 13 formed of suitable material, such as plywood, and also of rectangular shape, and being marginally secured to the frames 10 and 11, respectively, so that the edges of the side panels are flush with the outer edges of the corresponding frames.

Lower and upper bars 14 and 15 of rectangular cross sectional shape extend from the right-hand frame 10 at the rear end of this frame and at the upper and lower corners of the frame. These bars extend perpendicularly from the inner side of the frame 10 and each bar is provided with a longitudinally extending groove of rectangular cross sectional shape in its forward side, as indicated at 16 and 17, respectively. Each of the bars 14 and 15 is also provided in the grooved portion thereof with a longitudinally extending slot, as indicated at 18 and 19. Cor-

ner blocks 20 and 21 are secured between the bars 14 and 15 and the corresponding top and bottom rails 22 and 23 of the frame 10 to maintain the bars substantially perpendicular to the frame, and a reinforcing strip 24 extends along the inner side of the rear upright 25 of the frame between the corner blocks 20 and 21.

Upper and lower horizontal bars 26 and 27 extend from the rear end of the left-hand frame 11 at its upper and lower corners and are disposed substantially perpendicular to the frame 11 and held in perpendicular relationship thereto by corner blocks, one of which is indicated at 28, disposed between the bars and the upper and lower rails of the side frame 11. Each of the bars 26 and 27 is of rectangular cross sectional shape and has a width substantially equal to the width of the grooves 16 and 17 in the bars 14 and 15. The bars 26 and 27 overlap the bars 14 and 15 and are received in the grooves 16 and 17 for sliding movement longitudinally of the bars 14 and 15. Each of the bars 26 and 27 has an aperture therein near its end remote from the side frame 11 and bolts 29 and 30 extend through the apertures in the bars 26 and 27, respectively, and through the slots in the related bars 14 and 15 and carry wing nuts 31 and 32 on their ends at the rear sides of the bars 14 and 15 for clamping the bars 14 and 26 and 15 and 27 together in selected positions of longitudinal adjustment relative to each other.

Horizontal bars 33 and 34 are fixed to and extend laterally inwardly from the front end of the side frame 10, one at the upper and one at the lower front corner of this frame and are disposed substantially perpendicular to the frame 10. These bars are braced in their perpendicular relationship to the frame 10 by triangular corner blocks 35 and 36 secured between the bars 33 and 34, respectively, and the top and bottom rails 22 and 23 of the frame 10. Similar bars 37 and 38 extend perpendicularly from the front end of the frame 11, one from the front upper corner, and one from the front lower corner of this frame substantially perpendicular to the latter and are braced in their perpendicular relationship to the frame by corner blocks 39 and 40 disposed one between the top bar 37 and the top rail 41 of the frame 11, and the other between the bottom bar 38 and the bottom rail 42 of the frame 11.

The front bars 33 and 34 are shorter than the corresponding rear bars 14 and 15, and the front bars 37 and 38 are shorter than the corresponding rear bars 26 and 27 and do not overlap the

bars 33 and 34, all of the front bars having their front faces substantially in the same vertical plane. The bar 33 has its end remote from the frame 10 spaced, at all times, from the adjacent end of the bar 37 while the bar 34 has its end remote from the frame 10 spaced, at all times, from the adjacent end of the bar 38.

A front panel 43 is secured on the front sides of the bars 33 and 34 and has its edges flush with the upper and lower edges of these bars and one edge flush with the front vertical upright of the side frame 10. A similar front panel 44 is similarly secured to the bars 37 and 38 and has its end edges flush with the upper and lower edges of these bars and one side edge flush with the upright of the side frame 11. The front panels 43 and 44 have a width substantially equal to the length of the front bars and have their laterally inward edges somewhat spaced apart at all times.

The front bars 33, 34, 37 and 38 are provided with longitudinally extending slots 45, 46, 47 and 48 which also extend through the front panels 43 and 44. A third or front frame 49 of rectangular shape is disposed against the front surfaces of the front panels 43 and 44 and has a height substantially equal to the height of these panels. The front frame is provided with four apertures, and bolts, indicated at 50, 51, 52 and 53 extend, one through each of these apertures and through the corresponding slots 45, 46, 47 and 48 of the front bars and carry wing nuts for clamping the front frame 49 against the front surfaces of the front panels 43 and 44.

With this arrangement, both the overlapping rear bars and the spaced apart front bars can be clamped in selected positions of longitudinal adjustment relative to each other, so that the side panels 12 and 13 of the cabinet, with the associated side frames, can be spaced apart at any desired distance within the limits of expansion of the cabinet, as determined by the length of the bolt receiving slots in the arms, the arrangement being such that the side panels of the cabinet are held in substantially parallel relationship to each other as they are moved away from or toward each other to expand or contract the cabinet.

A screen 54 is mounted in the front frame 49 and conceals the opening between the adjacent edges of the front panels 43 and 44. This screen, as illustrated, comprises a stiff backing plate 55 of suitable material, such as plywood or heavy cardboard, and a fabric covering 56 is stretched over the outer surface of the backing plate.

The corner blocks at the bottom of the cabinet are provided with casters 57 reaching below cabinet to support the latter for movement on a floor or other horizontal support.

The invention may be embodied in other specific forms without departing from the spirit or essential characteristics thereof. The present embodiment is therefore to be considered in all respects as illustrative and not restrictive, the scope of the invention being defined by the appended claims rather than by the foregoing description, and all changes which come within the meaning and range of equivalency of the claims are, therefore, intended to be embraced therein.

What is claimed is:

1. In an expandable cabinet, first and second vertical side frames, said first side frame having upper and lower rear horizontal bars fixed to and extending laterally inwardly from rear por-

tions of said first frame and front upper and lower horizontal bars fixed to and extending laterally inwardly from forward portions of said first frame, said second side frame having upper and lower horizontal bars fixed to and projecting laterally inwardly from rear portions of said second side frame and upper and lower front horizontal bars fixed to and projecting laterally inwardly from forward portions of said second side frame, the rear lower bars of the side frames being in overlapping and sliding relation and the rear upper bars of the side frames being in overlapping and sliding relation, first means for clamping the overlapped rear upper and lower bars together in longitudinally adjusted relation to each other, the front upper and lower bars being shorter than the rear upper and lower bars and having their inwardly extending free ends in longitudinally spaced relation to each other, 15 front panels secured to and extending between the upper and lower bars of each of said side frames, and a front frame slidably engaged with the front faces of said front panels, and second means acting between said front frame and said 20 front panels for securing the front bars in longitudinally adjusted relation to each other.

2. In an expandable cabinet, first and second vertical side frames, said first side frame having upper and lower rear horizontal bars fixed to and extending laterally inwardly from rear portions of said first frame and front upper and lower horizontal bars fixed to and extending laterally inwardly from forward portions of said first frame, said second side frame having upper and lower horizontal bars fixed to and projecting laterally inwardly from rear portions of said second side frame and upper and lower front horizontal bars fixed to and projecting laterally inwardly from forward portions of said second side frame, the rear lower bars of the side frames being in overlapping and sliding relation and the rear upper bars of the side frames being in overlapping and sliding relation, first means for clamping the overlapped rear upper and lower bars together in longitudinally adjusted relation to each other, the front upper and lower bars being shorter than the rear upper and lower bars and having their inwardly extending free ends in longitudinally spaced relation to each other, 30 front panels secured to and extending between the upper and lower bars of each of said side frames, and a front frame slidably engaged with the front faces of said front panels, and second means acting between said front frame and said 35 front panels for securing the front bars in longitudinally adjusted relation to each other, 35 front panels secured to and extending between the upper and lower bars of each of said side frames, and a front frame slidably engaged with the front faces of said front panels, and second means acting between said front frame and said 40 front panels for securing the front bars in longitudinally adjusted relation to each other, 40 front panels secured to and extending between the upper and lower bars of each of said side frames, and a front frame slidably engaged with the front faces of said front panels, and second means acting between said front frame and said 45 front panels for securing the front bars in longitudinally adjusted relation to each other, 45 front panels secured to and extending between the upper and lower bars of each of said side frames, and a front frame slidably engaged with the front faces of said front panels, and second means acting between said front frame and said 50 front panels for securing the front bars in longitudinally adjusted relation to each other, 50 front panels secured to and extending between the upper and lower bars of each of said side frames, and a front frame slidably engaged with the front faces of said front panels, and second means acting between said front frame and said 55 front panels for securing the front bars in longitudinally adjusted relation to each other, said first and second side frames and said front frame being rectangular and comprising vertically spaced horizontal members and horizontal spaced vertical members connected to the horizontal members, a panel secured to the laterally outward side of each of said side frames, and a covering secured to the front side of said front frame.

CLARENCE A. TROUTMAN.
